TOY LAMP POST

Filed March 26, 1925

Patented Sept. 14, 1926.

1,599,721

UNITED STATES PATENT OFFICE.

HENRY H. ROSCHEN, OF BALTIMORE, MARYLAND.

TOY LAMP-POST.

Application filed March 26, 1925. Serial No. 18,517.

This invention relates to improvements in toy lamp posts.

The primary object of this invention is the provision of a toy lamp post, which may be used for supporting an electric bulb and means to conduct current to the same, and which may be constructed durably, neatly, and economically.

A further and important object of this invention is the provision of a lamp post constructed of a plurality of parts which may be economically manufactured, and compactly assembled in a stable and durable relation.

A further object of this invention is the provision of an electric lamp post, which embodies a novel U-shaped top portion, constructed of a plurality of parts by means of which to economically construct the same and assemble an electric cable therein which leads to an electric bulb adapted to be supported by a socket.

Other objects and advantages of this invention will be apparent during the course of the following detailed description.

In the drawing, wherein for the purpose of illustration is shown only a preferred embodiment of the improved toy lamp post,

Figure 1 is a side elevation of the improved toy lamp post.

Figure 2 is a sectional view taken longitudinally of the lamp post, showing operating details of construction.

Figure 3 is a fragmentary front elevation, partly in section, showing more particularly the upper portion and construction of the lamp post.

Figures 4, 5 and 6 are cross sectional views taken substantially on their respective lines in Figure 1 of the drawing.

In the drawing, wherein similar reference characters designate corresponding parts throughout the several views, the letter A may generally designate the improved lamp post, which may include a base 10; vertical standard 11; the top U-shaped bend or gooseneck portion 12; and bulb 13 adapted to be supported at the lower free end of the U-shaped portion 12.

Toy lamp posts, which have heretofore been marketed are in the main of flimsy construction, and are not adaptable for supporting incandescent lamps which are properly wired so that it is only necessary to connect current conducting wires to the base of the post for illuminating the lamp. In

the type of lamp post herein described, the assemblage of parts is rendered easy incident to the construction of the same, and the post is properly wired so that it is only necessary to connect lead-in wires to the base of the post, to proper terminals provided thereon, in order to illuminate the bulb supported by the post.

The base 10 is preferably formed of cast metal, which is preferably a lead alloy, and the walls of the same are relatively thick so that the same is of considerable weight to properly support the lamp post without attachment to a floor surface. This base 10

preferably includes a platform 20, which may be polygonal in outline, or round, and which is preferably provided with depending lugs 21, so that the platform 20 may be carried above the ground surface or floor surface 22 upon which the lugs 21 rest, as is illustrated in Figure 1 of the drawing. Upwardly extending from the platform 20, and integral therewith is a vertically arranged tapered portion 23, which is of course a part of the base 10, and which is hollow, providing a compartment 24 which opens downwardly thru the base. At its upper end the portion 23 of the base 10 is provided with an opening 25 therein, adapted to snugly receive the lower end of the vertical tubular standard 11.

The standard 11 is preferably of any approved material, such as seamless brass tubing, but the same may have a seam if desired. The lower end thereof as before mentioned is fixed in the opening 25 of the base 10, and may be soldered therein, as at a point 26, or in any other approved location. This tube 11 provides a passageway 28 communicating with the compartment 24, and at its upper end opening at the top edge.

Referring to the construction of the U-shaped top 12, the same is preferably sectionally formed of the parts 30 and 31, which are complementary in providing the top construction 12. These parts 30 and 31 are U-shaped as to length, and in cross section are concavo-convex, each of the same providing a groove therein. In other words, the U-shaped tube 12 is split longitudinally, and when the parts 30 and 31 are assembled to provide the said tube construction 12, the grooves thereof face each other to provide the passageway 33 therethrough. It is preferred that one of the sections, such as the section 30, be provided with oppositely

disposed pairs of clamping clasps or lugs 35, which are of course integral with the part 30, and when the parts 30 and 31 are assembled in edge abutting relation to provide the passageway 33 the clasps or lugs 35 are then bent about the convex exterior surface of the part 31, until the ends of each pair of said lugs 35 meet, preferably in overlapping relation, as is illustrated in Figure 6 of the drawings, and the free ends of said lugs or clasps 35 are then soldered, as at 38. These parts 30 and 31 are formed of sheet metal, and can readily be stamped in the sectional form above described and as is illustrated in the drawing.

The goose-neck construction 12 preferably provides the bulbular enlargement 39 annularly about an end of the same, and adjacent thereto the same provides the end portion 40 adapted to fit into the passageway 28 of the vertical standard 11, and to be secured thereto in any approved manner. Soldering at the point 41 may be resorted to for securing the standard 11 and the top portion or construction 12 together. It is to be noted that the enlargement 39 provides a stop for the top construction 12, by abutment against the top edge of the vertical standard 11. As a reinforcement to hold the U-shaped position of the top construction 12, it is preferred to provide the reinforcing scroll or web 45, which is preferably integral as a part of the section 31, and which is connected in integral manner with the section 31 at the ends thereof and at the intermediate portion thereof, substantially as is illustrated in Figure 1 of the drawing. This reinforces the construction 12 against bending of the tubular portion thereof, as can readily be understood, and the same may be stamped in the relation described, since it is flat.

At their free ends the sections 30 and 31 are each provided with a half-cylindrical shaped enlarged screw threaded segment portion, which when placed together provide the internally screw threaded socket 47 having the socket passageway 48 therethrough for detachably receiving the threaded plug end 49 of the electric light bulb 13. As a means of securely holding the segmental portions of the socket 47 together, it is preferred to provide a shade 50, which is preferably of one-piece formation, providing the annular clamping band 51 upwardly thereof which may be slipped over the segmental portions of the socket 47, and be secured thereto in any approved manner, as by threading on the socket, or as by being soldered at the edge 52. The shade 60 is of the ordinary type, in that the same extends downwardly in diverging relation over the socket 47, so that the lower portion of the bulb 13 projects therefrom.

Referring to the means of conducting an

electric current to the bulb 13, an insulated conducting wire 55 is provided, which extends upwardly through the base compartment 24; through the tube passageway 28, and which snugly fits in the passageway 33 70 of the U-shaped top construction 12. In fact, one of the primary advantages of forming the U-shaped construction 12 in sections is to enable the correct and expeditious placing of the insulated conducting wire 55 75 in the passageway 33. This wire 55 snugly fills the passageway 33, and thus aids in reinforcing the tube formed by the construction 12. At its end adjacent the socket 47 the wire extends through its insulation, and projects through eyelet 58 which is preferably centrally carried by an insulation fiber washer 59. The fiber washer 59 is crimped at its marginal portion by the assemblage of the sections of the socket 47, extending 85 transversely across the passageway through the socket 47, at the upper end of the socket passageway 48, and the wire extending through its insulation and through the eyelet 58 projects into the socket passageway 48, and is there preferably soldered or otherwise secured to a washer 60, although this washer 60 need not be provided, if it is desired to do away with the same. The wire 55 at the point where the same is soldered 95 to the washer 60 provides a contact for the bulb 13, and the bulb is grounded for its other contact to the socket 47. The wire 55 extends downwardly thru the base as above mentioned, and at its lower end extends into the space below the platform 20, and is stripped of its insulation and secured to the head 65 of a terminal screw 66, which is preferably insulated from the base 10. The wire 55 is preferably clamped by the screw head 65, although the same may be soldered thereto, if desired. The terminal screw 66 includes a shank 67 which extends upwardly through an insulation bushing 68 provided in a passageway 69 which is cast in the 110 base 10, and insulation washers 70 and 71 are provided below and above the base platform 20, to thoroughly insulate the terminal of the wire 55 from the base 10 and the lamp post A. A nut 73 is provided in screw threaded engagement with the shank 67 for clamping against the top washer 71, and at the upper screw threaded end of the terminal screw 66 a thumb adjusting nut 74 is provided, by means of which to clamp a lead-in wire (not shown) between the said nut 74 and the nut 73, as will be readily understood. As one terminal of the bulb 13 is grounded on the lamp post, it is preferred to provide a terminal screw 80 grounded on the base 10, having a head abutting the bottom of the platform 20, and a shank extending upwardly through a passageway 81 cast in the base platform 20. The upper screw threaded end of the clamping bolt or mem- 130

ber 80 receives a nut 82 by means of which to clamp the same in fixed relation on the platform 20, and is provided upwardly thereof with a thumb adjusting nut 83 by means to clamp a second lead-in wire (not shown) between the said nuts 82 and 83, as can be readily understood.

From the foregoing description of this invention it is obvious that an improved toy lamp post has been provided, which possesses novel features in that the same is formed of materials which may be economically manufactured and assembled to provide a very durable lamp post. In order to connect the bulb 13 in the circuit it is merely necessary to clamp the lead-in wires to the two terminals on the platform 20. The upper portion of the toy lamp post has been formed to overcome the flimsy top constructions for lamp posts which have heretofore been marketed. By sectionally forming the top structure 12, not only is an economical structure provided, but the conducting cable 55 may be accurately assembled to assist in the reinforcing of the top structure 12, and the washer 59 may be properly positioned to reinforce the socket 47, and counter the clamping effect which the shade 50 has in retaining the parts of the socket 47 together.

Various changes in the shape, size, and arrangement of parts may be made to the form of invention herein shown and described, without departing from the spirit of the invention or the scope of the claims.

I claim:

1. In a lamp post construction the combination of a hollow vertical standard having a passageway therethrough, a substantially U-shaped head split longitudinally thereof into a pair of substantially U-shaped complementary grooved sections, said U-shaped head at one end having the sections thereof disposed within the passageway of said standard at the top of the standard to align the passageways of the standard and U-shaped head and to hold the sections of the U-shaped head into assembled relation at said end of the U-shaped head, said U-shaped sections of the U-shaped head at the free ends thereof having complementary socket parts, means engaging about said socket parts to hold them into assembled relation and to hold the U-shaped sections of the U-shaped head in assembled relation at the free end thereof, a bulb for the socket, and a conducting wire extending thru the passageways of the standard and U-shaped head to the socket in an operative relation with respect to the bulb.

2. In a lamp post construction the combination of a hollow vertical standard having a passageway therethrough, a base upon which the standard is supported, said base being hollow and having a compartment with which the passageway of the standard

communicates, a substantially U-shaped head split longitudinally into a pair of grooved sections, said sections being connected with the grooves in facing relation to provide a passageway, said U-shaped head being connected at one end thereof in the top of the vertical standard to align the passageways of the standard and U-shaped head, each section of the U-shaped head at the free end thereof having an enlarged screw threaded segment, said segments when the sections of the U-shaped head are assembled being also in an assembled cylindrical relation to provide an internally screw threaded lamp bulb receiving socket, and a conducting wire extending thru the compartment of the base thru the passageway of the vertical standard and the passageway of the U-shaped head into an operative relation with the screw threaded socket.

3. In a toy lamp post the combination of a base, a top construction for the base including a pair of substantially U-shaped sections, means connecting the sections together to provide a passageway therealong, means connecting said top construction to said base, each of said sections at the free end thereof providing an enlarged threaded segment so that when the sections are assembled said segments will provide an internally screw threaded socket, a detachable lamp bulb for said socket, means for conveying current to said lamp bulb, and a shade exteriorly about the enlarged segments of said socket for holding the same together.

4. In a toy lamp post the combination of a base, a top construction for the base including a pair of substantially U-shaped sections, means connecting the sections together to provide a passageway therealong, means connecting said top construction to said base, each of said sections at the free end thereof providing an enlarged threaded segment so that when the sections are assembled said segment will provide an internally screw threaded socket, a detachable lamp bulb for said socket, means for conveying current to said lamp bulb, a shade exteriorly about the enlarged segments of said socket for holding the same together, and a washer secured within said socket at the inner end thereof for supporting the segments thereof.

5. In a toy lamp post the combination of a base, a top construction of U-shaped formation including a pair of sections concavo-convex in cross section providing a groove therealong, one of said sections having laterally extending lugs for gripping about the other section when the grooves of said sections are in facing relation to provide a passageway, means for assembling the top construction to said base upwardly thereof, each of said sections of the top construction at

the free end thereof providing an enlarged screw threaded segment, said sections when held together having said segments in formation to provide an internally screw threaded socket, an insulation fiber disc carried at the base of socket passageway, a bulb for detachable threading in said socket, and a wire extending through said passageway of the top construction and connected 10 through said insulation washer to provide a contact in said socket for said bulb.

6. In a toy lamp post the combination of a base, a top construction of U-shaped formation including a pair of sections concavo- 15 convex in cross section providing a groove therealong, one of said sections having laterally extending lugs for gripping about the other section when the grooves of said sections are in facing relation to provide a 20 passageway, means for assembling the top construction to said base upwardly thereof, each of said section of the top construction at the free end thereof providing an enlarged screw threaded segment, said sections when 25 held together having said segments in formation to provide an internally screw threaded socket, an insulation fiber disc carried at the base of said socket passageway, a bulb for detachable threading in said 30 socket, a wire extending through said passageway of the top construction and connected through said insulation washer to provide a contact in said socket for said bulb, and a shade secured exteriorly about 35 the segments providing said socket adjacent said insulation washer within the socket whereby to reinforce said socket.

7. In a toy lamp post the combination of a heavy metal base including a platform and 40 providing a passageway upwardly therethrough, a tubular standard supported by said base providing a passageway aligning with the passageway of the base, a clamping terminal grounded on said base, a second 45 clamping terminal carried in insulating relation by said base, a U-shaped top structure secured to the upper end of said tubular shaped standard including a pair of grooved sections split longitudinally of the 50 top structure, one of said grooved sections having laterally extending fingers to grip about the other whereby to hold the sections together with the grooves facing to provide a U-shaped passageway communicating at 55 one end with said passageway of the upright standard, the other of said top structure sections providing a reinforcing web, each of said sections of the top structure at its free

end providing an enlarged threaded segment which provide an internally screw threaded 60 socket when the sections are together, an insulation washer clamped in position by said segments in the base of said socket adjacent the passageway of said top structure, a conducting wire having insulation thereon extending through said insulation washer to provide a contact in said socket, said wire and insulation snugly extending in reinforcing relation through the passageway of the top structure and downwardly through the passageways of the standard and base for connection at its lower end to the terminal which is insulated from said base, and a lamp bulb for said socket.

8. In a toy lamp post the combination of a heavy metal base including a platform and providing a passageway upwardly therethrough, a tubular standard supported by said base providing a passageway aligning with the passageway of the base, a clamping 80 terminal grounded on said base, a second clamping terminal carried in insulating relation by said base, a U-shaped top structure secured to the upper end of said tubular shaped standard including a pair of grooved 85 sections split longitudinally of the top structure, one of said grooved sections having laterally extending fingers to grip about the other whereby to hold the sections together with the grooves facing to provide a U- 90 shaped passageway communicating at one end with said passageway of the upright standard, the other of said top structure sections providing a reinforcing web, each of said sections of the top structure at its free 95 end providing an enlarged threaded segment which provide an internally screw threaded socket when the sections are together, an insulation washer clamped in position by said segments in the base of said socket adjacent the passageway of said top structure, a conducting wire having insulation thereon extending through said insulation washer to provide a contact in said 100 socket, said wire and insulation snugly extending in reinforcing relation through the passageway of the top structure and downwardly through the passageways of the standard and base for connection at its lower end to the terminal which is insulated from said base, a lamp bulb for said socket, and a shade exteriorly secured in clamping 105 reinforcing relation about said socket segments.

HENRY H. ROSCHEN.
